DUPLEX PUMPING ENGINE

Arthur L. Leman, Houston, Tex., assignor, by
mesne assignments, to The National Supply
Company, Pittsburgh, Pa., a corporation of
Pennsylvania

Application February 9, 1937, Serial No. 124,829

5 Claims. (Cl. 121—114)

This invention relates to pumps, and more particularly to an improvement in steam driven duplex pumps of the type as ordinarily employed in oil field work for the pumping of mud or slush, or any other fluid, and particularly to the valve actuating mechanism thereof. In steam driven duplex pumps as heretofore used, it has ordinarily been necessary to place the steam chest and valves at a considerable height 5 above the steam cylinders, even though it has been recognized that such an arrangement was inefficient in that it requires steam ports of excessive length with the resultant large condensation losses and undue clearance. The necessity of positioning the steam chest and valves 10 at a sufficient height above the steam cylinders has arisen because of certain limitations imposed by the construction of the valve actuating mechanism.

20 In such a valve actuating mechanism the rock-shaft levers which are caused to oscillate by the piston rods must be of sufficient length to minimize their angle of oscillation in order to overcome excessive vertical movement at their lower ends. The length of the rockshaft levers 25 has therefore determined the minimum elevation of the rockshafts.

In the customary form of duplex steam pumps now in use it has been common practice to position one rockshaft above the plane of the valve operating rods and the other rockshaft below the plane of the operating rods. In this conventional construction the minimum elevation of the valve rods, and hence of the valve, is determined by 30 the length of the shorter of the rockshaft levers.

The principal object of this invention is to provide a steam driven duplex pump wherein there is provided a valve actuating mechanism 35 and wherein the steam chest and valves are positioned immediately adjacent the steam cylinders and which structure is such as to permit of the use of the desired length of the rockshaft levers.

40 Another object of this invention is to provide a steam driven duplex pump in which the steam valves are approximately the same length as the steam cylinders in order that the length of the steam ducts may be further reduced whereby 45 the clearance volume is reduced to a minimum.

Another object of this invention is to provide 50 a steam driven duplex pump in which the rockshaft stand portion of the valve actuating mechanism is enclosed in an oil tight housing 55 to protect the same from slush and other for-

5 eign matter, and wherein means are provided for the adequate lubrication of the parts.

A further object of this invention is to provide 10 a steam operated duplex pump including a valve actuating mechanism which includes a pair of reciprocating members having the dual purpose of actuating the steam valves and also acting as plungers for a pair of lubricant circulating pumps.

Other objects and advantages of this invention 15 it is believed will be apparent from the following detailed description of a preferred embodiment thereof as illustrated in the accompanying drawings.

In the drawings:

Figure 1 is a side elevation of the steam driven duplex pump shown partly in cross section and showing the outline and position of the improved valve actuating mechanism.

Figure 2 is an end view of the pump shown 20 partly in cross section.

Figure 3 is a sectional view of the water end 25 of the pump taken substantially on the line 3—3 of Figure 2.

Figure 4 is a sectional plan view of the valve 30 actuating mechanism taken substantially on the line 4—4 of Figure 6.

Figure 5 is a sectional view of the valve actuating mechanism taken substantially on the line 5—5 of Figure 4.

Figure 6 is a sectional view of the valve actuating mechanism taken substantially on the line 6—6 of Figure 4.

Figure 7 is an end elevation of the valve actuating mechanism partly in cross section taken 35 substantially on the line 7—7 of Figure 6.

Figure 8 is a fragmental sectional view taken substantially on the line 8—8 of Figure 5.

My invention as illustrated in its preferred 40 form in the accompanying drawings is applied to a steam driven duplex pump of the type commonly used to circulate slush or mud as used in the rotary system of well drilling. The entire pump is mounted on skids 20 in order to facilitate transportation and installation in the field. The principal elements or units of this pump 45 may be generally referred to as the steam end A, the water end B, and the valve actuating mechanism C. The steam end A includes cylinders 1 having steam pistons 2, a steam chest 3, and valves 4. In this particular structure the valves 4 are the balanced type commonly referred to as piston valves. Steam ducts 5 communicate between the steam chest and steam cylinders. The steam valves 4 are of novel de- 55

sign in that they are approximately the same length as the steam cylinders 1 and in that they permit the use of short, straight steam ports or ducts 5 at both ends of the cylinder 1. Short steam ducts are very desirable since they reduce condensation loss and clearance and therefore favorably affect the efficiency of the pump.

The water end B includes water cylinders 6, water pistons 7, suction passages 8, suction valves 9, and discharge valves 10 and a strainer 11. A spider 12 is provided as a means to adjust the pressure on the packing 13 around the removable liner 14 in order that the fluid may not pass from one end of the cylinder 6 to the other outside of the liner 14. The steam end of the piston rod 15 which operates through the stuffing box 16 is fixed at one end to the steam piston 2 and at the other end to the spool or crosshead 17. The water end of the piston rod 15 operates through the stuffing box 18 and is fixed at one end to the water piston 7 and at the other end to the same crosshead 17. In this way reciprocating motion imparted to the steam piston 2 is transmitted to the water piston 7.

It is of course understood that this duplex pump has two steam cylinders and two water cylinders (see Figure 2). In a general way the pump may be regarded as of two single pumps acting side by side.

The valve actuating mechanism C is mounted upon the frame of the pump between the steam end A and the water end B and serves to communicate reciprocating motion from the piston rods 15 to the steam valves 4, each valve being operated by the piston rod on the opposite side of the pump.

The valve actuating mechanism C includes a case 21 in which there is journaled rock shafts 22 and 23. Rock shafts 22 and 23 are in the same vertical plane. Rock shaft 22 extends through the case 21 at one side and carries the rocker arm 24 which is operated by the piston rod 15a through the piston rod crossheads 17a and roller 26a to cause the rock shaft 22 to oscillate as the piston rod 15a reciprocates. Similarly rock shaft 23 extends through the case 21 and is caused to oscillate by the rocker arm 25 and the piston rod 15 through the piston rod crosshead 17 and the roller 26. The parts designated by a numeral with the suffix a in the foregoing correspond to the parts given the same numeral but on the opposite side of the pump.

The rockshaft 22 carries an upwardly extending crank 27 and the rock shaft 23 carries a similar but downwardly extending crank 28. The axes of the pins 29 and 30 at the outer ends of the cranks 27 and 28 are substantially in the same horizontal plane. The crank 27 is pivotally connected to a link 31 which in turn is pivotally connected to its crosshead 33. Crank 28 is similarly connected to its crosshead 33a through a link 32. The crossheads 33 and 33a are slidably mounted in bearings within the case 21 and are caused to reciprocate by links 31 and 32 respectively. Their reciprocation is communicated to the valve actuating rods 34 which are directly connected to them and lie on their respective axes extended.

A novel and important feature of this arrangement is that it permits the crossheads 33 and 33a to be positioned at a low elevation with respect to the steam cylinders 1 without sacrificing the length of the rocker arms 24 and 25. The length of the steam ducts 5 may be thus kept at a minimum, allowing greater efficiency without causing greater excess of angularity of oscillation

and consequent undue vertical movement of the lower ends of the rocker arms 24 and 25.

The case 21 is held securely to the pump frame by means of studs 35 and nuts 36. The case covers 37, 38 and 39 permit access to the interior of the housing or case 21. The rock shaft cranks, links, and a portion of each crosshead are thus enclosed in a unitary structure and are protected from slush or other abrasive material.

In order to provide for adequate lubrication for my improved valve actuating mechanism, I have provided a novel oiling system wherein the crossheads 33 and 33a adjacent the water end B act as pump plungers in a simplified form of oil pump, thereby utilizing the reciprocating motion of the crossheads to pump lubricant for the bearing mechanism as well as to operate the valves. In order to accomplish this it is provided that when the crosshead 33a moves away from the water end B, a suction valve 40 opens and lubricant is drawn up from the reservoir 41 in the bottom of the case 21 through the passage 42 and into the chamber 43. When the crosshead 33a moves toward the water end B, suction valve 40 closes, discharge valve 44 opens, and the lubricant is forced up through the tube 45 into the upper reservoir 47. In the same manner the reciprocating motion of the crosshead 33 forces lubricant up through the tube 46 into the upper reservoir 47.

The bearings for rockshaft 23 are lubricated directly from the upper reservoir 47. The crank pins 29 and 30 receive lubricant from the upper reservoir 47 through the openings 48 and 49. Excess lubricant from the openings 48 and 49 falls into an intermediate reservoir 50 from which the bearings for the lower rock shaft 22 are lubricated. Oil overflows the intermediate reservoir 50 through small openings or canals 51 positioned immediately above each crosshead. A stream of oil is thus directed against each crosshead as it reciprocates. A portion of this oil makes its way through the crosshead supporting bearings 68, furnishing ample lubrication therefor. Oil which reaches the outer end of the bearings 68 is drained into the lower reservoir 41 through ducts 52. Another portion of the oil which falls on the crosshead flows through ducts 69 to lubricate the pivotal connection between the links 31 and 32 and their respective crossheads. Excess oil from the canals 51 falls into the lower reservoir 41 to be recirculated.

Oil is prevented from escaping through the bearings which support the rock shafts by means of suitable oil seals 53, 54. Oil seals 55 are placed near the inner ends of the bearings of the crossheads 33 and 33a to prevent the escape of the oil from the case 21 at the points where the crossheads pass through the case 21. These oil seals retain the lubricant within the case 21 and also act to exclude water, slush or other foreign material from passing into the case 21.

The rocker arm roller bearings 66 and 66a are lubricated through passages 57 which extend through the rocker arms 24 and 25 and terminate in fittings 58 through which lubricant is applied under pressure. Passages 67 and 67a are provided in the rollers 26 and 26a to permit lubricant to be forced therethrough to provide proper lubrication between the outer peripheries of the rollers 26 and 26a and the flanges of the crossheads 17 and 17a.

Figure 8 shows a detail of the water manifold 59 which is conveniently located in the lower corner of the case 21. Water is supplied under

pressure to the manifold 59 through intake 60 and discharges from the manifold through the outlets 61 and 61a. Water is then directed against the piston rods 15 and 15a through the pet cocks 62 and 62a.

The purpose of this flushing of the piston rods 15 and 15a is to wash off sand and slush that may accumulate thereon and thereby minimize abrasion between the rods 15, 15a and the packing 10 within the stuffing boxes 18.

The operation of the pump embodying my invention is: Steam admitted into the steam cylinder 1 alternately at one end and then at the other causes the steam piston 2 to reciprocate.

This motion is transmitted directly to the water piston 7 since both pistons are rigidly connected to the piston rod 15. As illustrated in Figure 1, when the water piston 7 moves to the right, fluid is drawn into the left chamber 64 through the suction passage 8 and at the same time other fluid is being discharged from the right chamber 65 through the discharge valve 10 and through the strainer 11. During this operation the left suction valve (not shown) and the right discharge valve 10 are open and all other water valves are closed. Similarly when water piston 7 moves to the left, fluid is drawn into the right chamber 65 through the right section valve 9 and at the same time the fluid which has just been drawn into the left chamber 64 is discharged through the left discharge valve 10 and through the strainer 11. Thus the water piston 7 discharges fluid during both directions of motion.

Since the pump has two sets of pistons and piston rods working side by side, it is necessary that there be a regulating device controlling the stroking of both sides of the pump. The valve actuating mechanism C serves in this capacity, operating both steam valves which in turn control the movement of the steam pistons. As explained above, the motion of each steam valve is controlled by the piston rod on the opposite side of the pump. Assuming the piston rod 15 illustrated in Figure 1 to be called the near piston rod, and the piston rod 15a on the other side of the pump to be called the far piston rod, then the cycle of operation of the pump may be described as follows:

The near piston rod 15 moves to the right, causing the rocker arm 25 to move through its arc and move the crosshead 33a on the far side of the pump likewise to the right. Due to the necessary lost motion between the valve actuating rods and their respective steam valves, the steam valve on the far side of the pump does not move until the near piston rod 15 is almost at the end of its stroke. The far steam valve then moves to the right, admitting steam into the left end of the far steam cylinder. The far steam rod 15a then moves to the right, moving its rocker arm 24 through its arc and causes the near crosshead 33 to move to the left.

Near the end of the stroke of the far piston rod 15a, the lost motion between the near valve actuating rod 34 and its steam valve 4 is taken up, and steam valve 4 moves to the left, admitting steam through intake port 5 at the right end of steam cylinder 1.

The near piston rod then moves to the left, exhausting steam on the left of the piston through the left steam port 5e, and moving the rocker arm 25 through its arc, which in turn moves the far crosshead 33a to the left. The far steam valve moves to the left admitting steam to the right end of the far cylinder. The far

piston rod 15a then moves to the left, exhausting steam on the left side of the piston through an exhaust duct. Rocker arm 24 moves then through its arc, causing crosshead 33 to move to the right. Steam valve 4 moves to the right, admitting steam to the left end of the cylinder 1 and allowing steam on the right side of the steam piston 2 to exhaust through the right exhaust port 5. The near piston rod 15 moves to the right as before and the cycle of operation is then repeated. The operation as thus described constitutes one complete cycle and the cycle repeats as long as steam is supplied.

The steam which is being exhausted through the exhaust ducts 5e impinges upon a flaring section of the valve 4 with considerable force and tends to jerk the valve 4 and to violently take up the lost motion between it and its actuating rod 34. To overcome this tendency, baffle rings 63 are mounted upon the steam valves 4 as shown. The baffle rings 63 deflect exhausting steam from the flaring sections of the valve 4 and counteract the force at said flaring sections tending to move the valve longitudinally.

Having fully described my invention, it is to be understood that I do not wish to be limited to the details herein set forth, but my invention is of the full scope of the appended claims.

I claim:

1. In a steam operated pump, a steam cylinder, 30 a piston mounted therein, a steam manifold positioned adjacent each end of said cylinder, an exhaust chamber positioned between said steam manifolds, inlet passages between said manifolds and cylinder, exhaust passages between said cylinder and said chamber, a valve of substantially the same length as said cylinder and adapted to control the flow of steam to and from said cylinder through said passages, said valve having enlarged end portions slidably supported within a bore formed above said cylinder, means including a lost-motion connection to actuate said valve, and baffle means secured to said valve between said enlarged end portions to counteract the reactive force acting against the face of an end portion exposed to the exhaust chamber when steam is exhausted through said exhaust passages into said chamber.

2. In a valve actuating mechanism for steam operated duplex pumps, the combination of a housing, a pair of rockshafts rotatably supported in the housing and each having one end extending therethrough, one of said rockshafts having an upwardly extending crank, and the other having a downwardly extending crank, a pair of parallel crossheads slidably mounted in spaced bearings carried by said housing substantially below the level of either of said rockshafts, a link pivotally connected at one end to each crosshead intermediate its bearings and at the other end to one of said cranks, and means operatively associated with the extending end of each rockshaft to impart oscillatory motion thereto.

3. In a valve operating mechanism for steam operated duplex pumps having a pair of piston rods disposed in horizontal parallelism, the combination of a pair of parallel rockshafts positioned above the plane of said piston rods, the axis of each rockshaft being horizontal and in a common plane perpendicular to the plane of the piston rods, each rockshaft having a downwardly extending lever fixed thereon adapted to be actuated by a piston rod, an upwardly extending crank fixed upon one of said rockshafts and a downwardly extending crank fixed upon the other of said

rockshafts, a pair of valve operating crossheads disposed in parallelism with said piston rods and positioned in a horizontal plane substantially below the level of either of said rockshafts, guide 5 means for said crossheads, and a link connecting each crosshead to a corresponding crank.

4. In a valve actuating mechanism for steam driven duplex pumps of the direct acting type, the combination of a supporting case, a pair of 10 horizontal shafts rotatably supported by said case, a pair of valve actuating members slidably supported by said case and positioned in a plane below both of said shafts, separate means operatively associated with each shaft and a corresponding 15 valve actuating member and adapted to impart reciprocating motion to the latter upon oscillatory movement of the former, and acting to give said members opposite directions of travel upon movement of said shafts in the same angular 20 direction.

5. In a valve actuating mechanism for steam driven duplex pumps of the direct acting type having a pair of parallel piston rods, pistons on said rods, a pair of adjacent steam cylinders in

which said piston rods are adapted to reciprocate, and a steam valve associated with each cylinder; the combination of a pair of horizontal shafts rotatably supported above the plane defined by said piston rods, separate means operatively associated 5 with each one of said shafts and a corresponding piston rod, and adapted to impart oscillation to the shafts upon reciprocation of the piston rods, a pair of valve actuating members each adapted to actuate one of said steam valves, said members 10 being slidably supported in a plane below both of said shafts and positioned in parallel relation with respect to said piston rods, means operatively associated with each shaft and a corresponding valve actuating member, and adapted to impart 15 reciprocation to the latter upon oscillation of the former, said members having opposite directions of travel for movement of said shafts in the same angular direction, whereby one of said piston rods is adapted to move the valve for the adjacent 20 steam cylinder in a direction opposite to that of its own movement.

ARTHUR L. LEMAN.
